UNITED STATES PATENT OFFICE.

WALTER K. DWELLE, OF HOUSTON, TEXAS, ASSIGNOR OF FORTY PER CENT TO JOHN T. DEAVER, TWELVE AND ONE-HALF PER CENT TO JAMES LAWLER, AND SEVEN AND ONE-HALF PER CENT TO C. C. CUNNINGHAM, ALL OF HOUSTON, TEXAS.

AEROPLANE PROPELLER.

Application filed October 17, 1927. Serial No. 226,713.

This invention relates to new and useful improvements in an aeroplane, and has particular relation to a novel means of propelling the same.

5 One object of the invention is to provide, in an aeroplane, a novel means for propelling the aeroplane.

Another object of the invention is to provide, in an aeroplane, spiralled propellers, 10 enclosed, or housed in, so that they will not be liable to cause injury to the operator, or to bystanders, or to become broken, and to the further end that they will be practically noiseless and more efficient than propelling

15 means for air craft now in common use.

A further feature of the invention is to provide, in an aeroplane, a propelling means which includes a surrounding housing provided with chambers which are adapted to 20 contain any suitable gas, which is lighter than air, and which will add buoyancy to the aeroplane.

With the above and other objects in view this invention has particular relation to certain novel features of construction, operation 25 and arrangement of parts an example of which is given in this specification and illustrated in the accompanying drawings, wherein:—

30 Figure 1 shows a horizontal, longitudinal sectional view of the device.

Figure 2 shows a front elevation thereof.

Figure 3 shows a sectional view taken on the line 3—3 of Figure 1.

35 Figure 4 shows a cross sectional view taken on the line 4—4 of Figure 1, and

Figure 5 shows a cross sectional view taken on the line 5—5 of Figure 3.

Referring now more particularly to the drawings, wherein like numerals designate similar parts in each of the figures the numeral 1 designates the fuselage, as a whole, which, if desired, may have double walls to provide a space 2 to contain a light gas to 45 make the aeroplane more buoyant. The numeral 3 designates a motor, of conventional construction, mounted in the fuselage and having the forwardly extending propeller shaft 4, operatively connected therewith.

50 The outer, or forward, end of this shaft has a bearing in a spider 5 which is fixed in the forwardly flared forward end 6, of the propeller housing, which is designated generally by the numeral 7. Fixed on the forward end

of said shaft there is a spiralled vane 8, forming a propeller, and that portion of the housing within which said vane is located has a Venturi passageway therethrough.

The housing 7 is anchored to, and extends forwardly from, the fuselage 1 and arranged 60 concentrically within it, in the rear of the vane 8 there is an inner housing 9 having a Venturi shaped passageway 10 in, the forward end of which there is another spiralled vane 11, fixed on the shaft 4.

65 There are the spaced partitions 12, 13, spanning the housing 7 and fixed to the walls thereof.

70 There are the four intermediate vanes, or propellers, 14, disposed around the propeller 11 and fixed on the lengthwise shafts 15, and enclosed, or housed, in the Venturi passageways 16. The forward ends of the shafts 15, have bearings, as 17, in the spiders 18, provided in the housing 7 and the rear ends of 75 said shafts have bearings in the respective partitions 12, 13 and fixed on said shafts 15 between said partitions are the spur gears 19 which are in mesh with, and driven by the master gear 20, which is located between the 80 partitions 12, 13 and which is fixed on the forward end of the tubular shaft 21. This shaft 21 telescopes over the shaft 4 and runs in the end bearings 22, 23 the former of which is in the forward end of the fuselage and the latter of which is in the partition 13.

85 The rear, or inner, end of the shaft 21 is formed with a cone clutch member 24 and splined on the shaft 4 there is a cone clutch member 25 said clutch members forming a 90 clutch which is normally held engaged by the coil spring 26 which surrounds the shaft. 4 and is interposed between the motor 3 and said clutch member 25.

95 The hub of the clutch member 25 is operatively connected with, and turnable in, the yoke 27 into which the adjacent end of the pivoted lever 28 is formed. Connected to the other end of this lever there is a shift rod 29 through the manipulation of which the clutch 100 may be released and the propellers, driven from the shaft 21, stopped.

105 Rotatably mounted in suitable bearings carried by the partitions 12, 13 are the intermediate spur gears 30, which are in mesh with and driven by the master gear 20, and which are also in mesh with and drive the spur gears 31 located between the partitions

12, 13 and fixed on the forward ends of the shafts 32. These shafts 32 have bearings in the forward end of the fuselage and in the partitions 12, 13 and have the spiralled outer 5 vanes, or propellers 33 fixed thereon, and enclosed within the Venturi passageways 34 through the housings 35.

The passageways 10, and 34 have the outlet openings 36, and 37 respectively into a discharge passageway 38 through which the air from the propellers may be discharged through any suitable outlet passageway.

As the machine moves forwardly the air is drawn in through the housing 7 and is caught 15 up successively by the vanes 8, 11, 14 and 23 successively and is finally discharged through the openings 36 and 37.

The entire housing 7 is surrounded by a forwardly converging hood 39, which is secured at its rear end to the forward end of the fuselage, and at its forward end to the forward end of the housing 7.

On account of the irregular outside contour of the housing 7 there will be formed 25 the chambers 40, between it and the hood 39, and likewise there will be formed the chambers 41 between the housings surrounding the propellers 11 and 14, and these chambers 40 and 41 may be filled with a suitable light 30 gas to increase the buoyancy of the aeroplane.

The various Venturi tubes disclosed and the independent propellers working therein provide a construction which will relieve the main propeller shaft of a portion of the 35 entire load and it is believed that the Venturi form of the passageways in which the various propellers are located will assist in relieving or discharging the air from the respective propellers after the propellers have 40 acted on said air, that is, will assist in the quick discharge of the air backwardly.

While I have shown and described only one form of the invention it is obvious that mechanical changes may be made therein and 45 equivalents substituted for the parts shown and I hereby reserve the right to make such mechanical changes and adaptations as may be found desirable so long as I do not depart from the principle of the invention as 50 comprehended within the scope of the appended claims.

What I claim is:—

1. A housing carried by the forward end of an aeroplane fuselage and having a central air passageway therethrough, a plurality of side air passageways therethrough, propelling means in said respective side passageways and enclosed by said housing.

2. A housing adapted to be carried by the forward end of a fuselage and having an air passageway therethrough, a plurality of propelling means in said passageway, and means for driving said propelling means.

3. A housing adapted to be carried by the 65 forward end of a fuselage of an aeroplane

and having a central air passageway therethrough, a plurality of side air passageways therethrough, propelling means in said respective side passageways and enclosed by said housing and means operatively connected to the propelling means and adapted to drive the same.

4. A housing adapted to be attached to the fuselage of an aeroplane having a forwardly flared central air passageway therethrough 75 of a propelling means enclosed by the housing and located in said passageway, said propelling means comprising a drive shaft and a spiralled vane fixed thereon.

5. A forwardly extending housing adapted to be carried by the front end of a fuselage, and having a central air passageway therethrough and a plurality of side air passageways, communicating with said central passageway, propellers enclosed by the housing 85 and located in the respective side passageways.

6. A forwardly extending housing adapted to be carried by the front end of a fuselage, and having a central air passageway therethrough and a plurality of side air passageways communicating with said central passageway, propellers enclosed by the housing 90 and located in the respective passageways, a driving shaft on which one of said propellers 95 is fixed and operative connections forming driving means between said shaft and the other propellers.

7. A forwardly extending housing adapted to be carried by the front end of a fuselage, 100 and having a central air passageway therethrough and a plurality of side air passageways communicating with said central passageway, propellers enclosed by the housing and located in the respective passageways, 105 said passageways forming Venturi tubes.

8. A forwardly extending housing adapted to be carried by the front end of a fuselage, and having a central air passageway therethrough and a plurality of side air passageways communicating with said central passageway, propellers enclosed by the housing 110 and located in the respective passageways, said propellers being separately enclosed, 115 said housing being provided with enclosed gas containing chambers.

9. A forwardly extending housing adapted to be carried by the front end of a fuselage, and having a central air passageway therethrough and a plurality of side air passageways communicating with said central passageway, propellers enclosed by the housing and located in the respective passageways, 120 a driving shaft on which one of the propellers is fixed, an independent driving shaft operatively connected with other of the propellers and means for clutching said shafts together and for disengaging them.

10. A propeller comprising a housing, a propelling means enclosed by said housing,

said housing having enclosed gas containing chambers.

11. A forwardly extending housing adapted to be carried by the front end of a fuselage, and having a central air passageway therethrough and a plurality of side air passageways communicating with said central passageway, propellers inclosed by the housing and located in the respective passageways, a driving shaft on which one of said propellers is fixed, a tubular shaft fitted over said driving shaft and operatively connected with said other propellers.
12. A forwardly extending housing adapt-

ed to be carried by the front end of a fuselage, 15 and having a central air passageway therethrough and a plurality of side air passageways communicating with said central passageway, propellers inclosed by the housing and located in the respective passageways, a 20 driving shaft on which one of said propellers is fixed, a tubular shaft fitted over said driving shaft and operatively connected with said other propellers, and a clutch through which said shafts may be engaged and released. 25

In testimony whereof I have signed my name to this specification.

WALTER K. DWELLE.
